UNITED STATES PATENT OFFICE.

EARL W. NEAL, OF NEW YORK, N. Y., ASSIGNOR TO WESTERN ELECTRIC COMPANY,
INCORPORATED, OF NEW YORK, N. Y., A CORPORATION OF NEW YORK.

GRID-LINING METHOD AND MACHINE.

Application filed February 17, 1919. Serial No. 277,614.

To all whom it may concern:

Be it known that I, EARL W. NEAL, a citizen of the United States, residing at New York, in the county of New York, State of New York, have invented certain new and useful Improvements in a Grid-Lining Method and Machine, of which the following is a full, clear, concise, and exact description.

10 This invention relates to the manufacture of grid electrodes for vacuum tubes, and more particularly to methods and devices for alining and straightening the cross-wires and frames of such grids after they have 15 been constructed in substantially their final form.

In process of welding the fine cross-wires of certain forms of grids to the side members or frames, the cross-wires are often 20 bent out of their proper position, which is parallel to each other and in a common plane. This, if not corrected, would result in a grid surface lacking in uniformity, and also in the danger of the grid contacting 25 with one of the other electrodes in the tube. For similar reasons, it is necessary that the side wires or frames of the grid, if bent, be restored to their proper position.

It is the object of this invention to provide 30 a simple, easily operable device for straightening and alining grids which have become distorted as above described or from other causes.

The mechanism which has been devised 35 to carry out this object, comprises a pair of clamps for holding opposite sides of a grid and relatively movable wedge-like spreading members adapted to engage the clamps when attached to a grid and thereby to 40 stretch the grid. The opposed faces of the spreading members have wedge-shaped grooves which may assist in alining the grid cross-wires.

The invention will be more fully understood 45 from the following detailed description and claims taken in connection with the accompanying drawings in which Fig. 1 is a detail perspective view showing a grid with one of the clamps attached thereto; Fig. 2 is a detail perspective view partly 50 broken away showing the spreading members; Fig. 3 is an end elevation partly in section showing the principal elements of the machine; Fig. 4 is an end elevation on a

reduced scale showing the complete machine.

Referring to the drawings by reference numerals, the grid 10, as shown, is of a double form having cross-wires 11 and loop-shaped side frames 12, the cross-wires 11 being of relatively much finer wire than the wire forming side frames 12. The clamps 13 comprise a block 14 of a form adapted to be inserted within the side frames 12, and pivotally connected to block 14 is 65 a pair of manually operated jaws 15 which are normally held in closed position by spring 16. On the block 14 are abutments 17 which adjust the position of the grid. Similar clamps 13 are provided for each 70 side of the grid. Cooperating with the clamps 13 are a stationary wedge-shaped spreading member 18 and a movable wedge-shaped spreading member 19, the free edges of the jaws 15 being bevelled to correspond 75 to the inclined surfaces 20 of the members 18 and 19. The movable spreading member 19 is attached to a plate 21 which is mounted for vertical reciprocation on four posts 22 secured to the plate 23. The 80 spreading member 18 is removably positioned on the plate 23 by means of guide posts or pins 24.

Referring to Fig. 4, extending upwardly from plate 21 is a rigid standard 25, and 85 pivotally connected to standard 25 is an operating lever 26 fulcrumed to the bracket 27 which is secured to a table or other suitable support 28. A sliding weight 29 is mounted on the outer end of lever 26, and 90 this weight is so adjusted that the spreading member 19 is normally held in upper position. A foot lever 30 is connected to lever 26 by means of a link 31. Tapered pins 32 (Fig. 2) are attached to the movable member 19, and cooperate with recesses 33, in the stationary member 18 for the purpose of 95 alining members 18 and 19, only one of pins 32 being shown in the drawing. The opposing faces of members 18 and 19 have a series of parallel ribs 34 having wedge-shaped grooves 35 therebetween. These grooves 35 are spaced to correspond with the cross-wires 11 of the grid.

The operation of the machine is as follows: Clamps 13 are attached to opposite sides of a grid which is to be straightened, and are placed on spreading member 18

when the latter is in some such position as that shown in Fig. 4. Member 18 is then moved into position between the pins 24, and the movable spreading member is depressed by means of foot-lever 30. The wedging action of members 18 and 19 exerts lateral pressure on the clamps 13, thus stretching and straightening the cross-wires 11, and at the same time the pressure 10 on jaws 15 insures the straightening of side frames 12. The cross-wires on opposite sides of the double grid pass into the corresponding grooves 35 which assist in alining and straightening the cross-wires.

15 While an embodiment of the machine has been shown and described which is adapted to straighten a double grid such as that shown at 10, it is obvious that the invention is not limited to the specific form shown 20 but may be varied within the limits of the appended claims.

What is claimed is:

1. A lining machine for grids having side members and cross members connected between said side members, comprising means for clamping said side members, substantially throughout their length and means including said clamping means for placing said cross members under tension.
2. In a grid lining machine for grids having side members and cross members connected between said side members, means for clamping said side members substantially throughout their length, and means for applying force in opposite directions to said clamping means.
3. The method of straightening a grid having side wires and cross wires, which comprises applying straightening forces to said side wires in a plurality of planes at an angle to each other, and placing said cross wires under tension.
4. In a grid lining machine, opposed clamps for holding a grid, each jaw of each of said clamps having provision for clamping said grid at a plurality of widely separated points, a support for said clamps, and means for moving said clamps apart.
5. In a grid lining machine, clamps for holding a grid, a support for said clamps, and wedge-shaped means for forcing said clamps in opposite directions.
6. In a grid lining machine, clamps for holding a grid, a wedge-shaped support for said clamps, and means for forcing said clamps towards the base of said support.
7. In a grid lining machine, clamps for

holding a grid, a wedge-shaped support for said clamps, and wedge-shaped means movable towards said support for forcing said 60 clamps in opposite directions.

8. In a grid lining machine for grids having parallel cross members, means for stretching said cross members including a wedge-shaped member, said member having 65 grooves at intervals corresponding to said cross members.

9. In a grid lining machine for grids having parallel cross members, means for stretching said cross members including a 70 wedge-shaped member, said member having wedge-shaped grooves at intervals corresponding to said cross members.

10. In a grid lining machine, a platform, a member mounted for vertical movement 75 above said platform, a removable grid support, means for positioning said support beneath said member, and means for gripping the edges of said grid, said means cooperating with said member to aline said grid.

11. A machine comprising clamps for holding an article to be operated upon, a support for said clamps, and wedge-shaped means for forcing said clamps in opposite directions.

12. A machine comprising clamps for holding an article to be operated upon, a wedge-shaped support for said clamps, and wedge-shaped means movable towards said support for forcing said clamps in opposite directions.

13. A clamp for grids having loop-shaped side members, comprising a block adapted to be inserted in one of said side members, and jaws pivotally mounted on opposite sides of said block, each of said jaws having a surface for pressing said side member against said block, and a surface for applying pressure to said side member in a different direction.

14. A clamp for grids having loop-shaped side members, comprising a block adapted to be inserted in one of said side members, jaws pivotally mounted on opposite sides of said block, each of said jaws having a surface for pressing said side member against said block and a surface for applying pressure to said side member in a different direction, and means yieldably holding said jaws in clamping position.

In witness whereof, I hereunto subscribe my name this 30th day of January A. D., 1919.

EARL W. NEAL.
